UNITED STATES PATENT OFFICE.

HARRY S. HART, OF CHICAGO, ILLINOIS.

DUMP-CAR CONSTRUCTION.

Application filed October 4, 1923. Serial No. 666,455.

The present invention relates to dump car construction.

In the type of dump car known as ballast car the parts are commonly arranged so that lading may be dumped either centrally of the tracks upon which the car is mounted or outside of said tracks. As ordinarily constructed, ballast cars are so arranged as to dump only between the trucks so that the lading in being dumped between the tracks will not interfere with said tracks. In ordinary constructions, a considerable proportion of the length of the car has been unused. When the ballast car is used for carrying coal or other lading which need not be dumped centrally of the track, ballast cars as ordinarily constructed do not have the maximum capacity which could be had within the over-all dimensions of the car.

An object of the present invention is to provide a railway dump car which combines the essential characteristics of a ballast car for selective side or center dumping with maximum carrying capacity for lading which need not be dumped between the tracks.

A further object is to provide a car having the advantages of selective side or center dumping between the trucks together with side dumping over and beyond the trucks.

A further object is to provide a modification of a well known type of selective dumping ballast car which will materially increase the capacity of said car for the carrying of lading which need not be centrally dumped.

Further objects will appear as the description proceeds.

Referring to the drawings:

Figure 1 is a view in side elevation of one embodiment of the present invention;

Figure 2 is a sectional view taken along the plane indicated by the arrows 2—2 of Figure 1; and

Figure 3 is a sectional view taken along the plane indicated by the arrows 3—3 of Figure 1.

The numeral 1 indicates a car, only one end portion of said car being illustrated.

Said car is provided with trucks at the two ends thereof, one of said trucks being indicated diagrammatically by the wheels 2, 2

thereof. Mounted at the bottom of the car between the trucks is certain dumping mechanism indicated as a whole by the numeral 3. The details of the dumping mechanism between the trucks need not be described specifically inasmuch as said details do not constitute the present invention. It may be stated, however, that said center dumping mechanism includes the sloping walls 4, 4, the swinging doors 5, 5, pivoted for movement about the axes 6, 6; the swinging doors 7, 7, pivoted for swinging movement about the axes 8, 8; the shedding portions 9, 9, attached to the center sill 10; the shedding cope 11 forming part of the center sill 10; and the sloping walls 12, 12, which deflect lading passing the doors 7, 7, to a position intermediate of the track upon which the wheels 2, 2 are mounted.

The doors 7, 7 are controlled by operating mechanism 13 which in turn is controlled by the shaft 14. The doors 5, 5 are controlled by the longitudinally extending shafts 15, 15.

Ballast cars for dumping lading between the trucks are ordinarily provided with sloping end walls 16, of which one is illustrated in dotted lines in Figure 1. Said sloping walls 16 direct lading to the dumping mechanism 3. According to the present invention, the sloping wall 16 instead of extending to the top of wall 1 near the end of the car, extends only to a line located above the corresponding truck and spaced materially from the end of the car. A vertical wall 17 indicated in dotted lines in Figure 1, is provided whereby to form with the side walls 1, 1 and end wall 17' of the car a receptacle 18 for such lading as coal, which need not be dumped centrally of the tracks. Each vertical wall 17 forms with its corresponding sloping wall 16 a structure triangular in cross section viewed transversely of the car, as shown in Figure 1.

Each receptacle 18 is provided with the sloping bottom walls 19, 19, as illustrated in Figure 3. Said sloping walls 19, 19 have a meeting edge disposed medially of the car whereby lading within said receptacle is directed wholly to the sides of the car. The numerals 20, 20 indicate swinging doors pivoted for movement about the axes 21, 21.

In Figure 3 the right-hand door 20 is shown in closed position and the left-hand door is shown in open position. The operating mechanism for controlling the doors 20, 20 is not illustrated inasmuch as said operating mechanism does not constitute any part of the present invention. Various types of door operating mechanism for dump cars are well known to those skilled in the art and no difficulties will be encountered by the skilled artisan in adapting any of the well known door operating mechanisms to the doors 20, 20.

It will be clear from the drawings and the description above, that the present invention provides a construction whereby the advantages of the selective dumping ballast car are retained in a construction of dump car having increased capacity for material which need not be directed between the tracks upon which the car is located. When the car is being used for ballast, said ballast may be selectively dumped between the tracks by operation of the doors 7, 7, or outside of the tracks by operation of the doors 5, 5, the ballast being directed towards said doors by means of the sloping walls 16 located near the ends of the car over the trucks. When it is desired to use the car for the carrying of coal or other lading which need not be deposited between the tracks, not only is the center portion of the car utilized, but the end receptacles 18 are utilized as well, the lading within said receptacles 18 being dumped outside the tracks past the doors 20, 20. By reason of the construction illustrated all of the capacity within the over-all dimensions of the car is utilized with the exception of the small portion of triangular cross-section between the sloping end wall 16 and the vertical wall 17 over each truck.

Though a preferred embodiment of the present invention has been described in detail, it will be clear that many modifications will occur to those skilled in the art, which modifications will not depart from the invention. It is intended to cover all such modifications which fall within the scope of the appended claims.

What is claimed is:

1. A dump car having trucks, a dump mechanism between said trucks for delivering lading either centrally of or outside of the tracks upon which the car is mounted, vertical walls forming with the end and side walls of said car, a receptacle at each end of said car over said trucks, inclined walls associated with said vertical walls for directing lading to the dump mechanism between the trucks, dump mechanism located adjacent to the ends of said car for delivering lading from said receptacles to regions outside of said tracks, and sloping walls, mounted adjacent to said vertical walls, dis-

posed transversely of said car and having their upper edges substantially coincident with said vertical walls, said sloping walls being disposed in positions to shed lading toward the dump mechanism located between said trucks. 70

2. A ballast car having trucks, dump means for depositing lading selectively between or outside of the tracks upon which said car is mounted, said dump means being located between said trucks, and sloping walls above said trucks for shedding lading to said dump means, said ballast car being provided with receptacles at the ends thereof, 75 said receptacles being provided with dumping mechanism for delivering lading at the side of said tracks, each of said sloping walls extending to a line disposed transversely of said car, which line lies materially above the bottom of the corresponding receptacle and 80 materially above said dump means, whereby the corresponding sloping wall forms an efficient dividing means between lading intended to be directed between the trucks and lading in the corresponding receptacle. 85 90

3. In combination, in a ballast car, side walls, trucks located at the ends of said car, sloping walls extending over said trucks and selective dumping mechanism located between said walls for delivering lading either 95 centrally of or outside of the tracks upon which said car is mounted, said car having adjacent to each end thereof a vertical wall connecting with a corresponding sloping bottom wall and forming with an end and side walls of said car a receptacle for the reception of lading, and dump mechanism for depositing lading from said receptacle to regions outside of said track. 100

4. A dump car comprising side walls, a truck at each end of said car, sloping walls converging toward the transverse center line of said car and located in a position above said trucks, a center sill extending longitudinally of said car, selective dumping mechanism located between said sloping walls and below said center sill, for selectively delivering lading inside of or outside of the tracks upon which the car is mounted, said car having a receptacle at each end, said 110 receptacle having sloping bottom walls located above said center sill for delivering lading outside of said tracks, each of said first mentioned sloping walls extending to a line disposed transversely of said car, which line lies materially above the bottom of the corresponding receptacle and materially above said selective dumping mechanism, whereby the corresponding sloping wall forms an efficient dividing means between lading intended to be directed between the trucks and lading in the corresponding receptacle. 115 120

5. A dump car having trucks, a dump mechanism between said trucks for deliver- 130

ing lading either centrally of or outside of the tracks upon which the car is mounted, vertical walls forming with the end and side walls of said car, a receptacle at each 5 end of said car over said trucks, inclined walls associated with said vertical walls for directing lading to the dump mechanism be-

tween the trucks, and dump mechanism located adjacent to the ends of said car for delivering lading from said receptacles to regions outside of said tracks. 10

Signed at Chicago, Illinois, this 1st day of October, 1923.

HARRY S. HART.
